WAVE LENGTH MODULATION

Murray G. Crosby, Riverhead, N. Y., assignor to
 Radio Corporation of America, a corporation
 of Delaware

Application March 9, 1940, Serial No. 323,077,
 which is a division of application Serial No.
 618,154, June 20, 1932. Divided and this ap-
 plication November 27, 1940, Serial No. 367,308

10 Claims. (Cl. 250—20.28)

This application concerns wave length modulation signalling means and methods and is a division of my United States application #323,077 filed March 9, 1940, now U. S. Patent No. 2,230,212, dated January 28, 1941, the latter application, in turn, being a division of my U. S. application #618,154 filed June 20, 1932, now U. S. Patent No. 2,229,640, dated January 28, 1941.

In describing my invention, reference will be made to the attached drawing wherein:

Figs. 1 and 2 are curves used in illustrating the principle involved in my method and means; while,

Figs. 3 and 4 are respectively a diagrammatical and a somewhat detailed showing of a wave length modulated wave translating means arranged in accordance with my invention.

As pointed out in detail hereinafter and in my two parent cases referred to above, if phase modulated wave energy is impressed on a frequency modulated wave receiver, the receiver output, i. e., the variations at signal frequency is not truly representative of the original modulating wave, but is modified as to amplitude substantially in proportion to its frequency. Thus, the lower modulation frequencies in the output are relatively attenuated as shown, for example, by the line A of Fig. 1. An output, as represented by the dotted line B of Fig. 1, is desired. In the said prior cases, means in the form of a correction network responsive to modulation frequencies and having a characteristic such as shown by the curve C of Fig. 2 is provided in the output of the receiver to additionally modify the modulating potentials from the detector in a sense to cure the previous described distortion. Thus, the overall effect is correct and is as indicated by curve B of Fig. 1.

In Figs. 3 and 4 has been shown an arrangement in which, by means of a novel circuit, a corrective effect, which is the converse of the manner in which phase modulated signals are distorted in a frequency modulation receiver, is applied to the signals. The distortion of the signal wave discussed hereinbefore and illustrated by curve A of Fig. 1 is created by virtue of the fact that phase modulated waves are being received on a frequency modulated signal receiver. On the other hand, if a circuit is set up which receives frequency modulation on a phase modulation receiver, a distortion is created which is the inverse of the undesired distortion obtained when phase modulation is received on a frequency modulation receiver. Obviously, if the phase modulated signal is passed through these circuits

in sequence, the distortion effects, which are the inverse of each other, will add or cooperate to give a resultant signal which is truly representative of the initial signal to be worked with. This might seem like a devious route to follow to receive phase modulation. Actually, it is not, however, and is, on the contrary, a convenient manner to receive phase modulated signals under certain conditions. The phase modulated signals are first received on a frequency modulated receiver, then converted by means of a local modulating means (transmitter) to frequency modulation, and received on a phase modulation receiver as shown in Fig. 3.

The logical assumption may be that, since a phase modulated signal receiver is used in this correction circuit, the phase modulations should be received directly on that unit. However, there are reasons for following the present course. First, the received signal output from phase modulated signals received on a frequency receiver, including correcting means is different from that received directly on a phase modulation receiver with respect to interference, fading, and tuning characteristics. Consequently, a corrected frequency modulation receiver (receiving phase modulated signals) will feed a certain circuit more suitably than a phase modulation receiver receiving the same signals directly. Second, the phase modulation system, including the local frequency modulation transmitter, when used for a correction circuit, in accordance with the present invention, is far more simplified than when the transmitter and receiver are at widely separated points. This may be realized by an inspection of the circuit of Fig. 4, which shows a correction circuit of this type in detail.

In Fig. 4, the signal frequencies to be corrected are applied from the detector of the frequency modulation receiver FMR tuned to and receiving the phase modulated signal picked up by the antenna to the input terminals of a transformer 50. The secondary winding of transformer 50 is connected to the control electrode 45 90 of an oscillation generator 91 of the dynatron type. The anode 92 is connected with an oscillatory circuit 93 in which oscillations at high frequency are developed by producing a negative resistance effect in the anode cathode circuit, as disclosed more in detail in United States application Ser. No. 608,383, filed April 30, 1932, now Patent #2,085,739, issued July 6, 1937. The high frequencies generated by the dynatron oscillator are modulated in frequency, as disclosed more 50 in detail in the above identified application. The

modulated oscillations are impressed from the circuit 93 on to a winding 94, and from winding 94 in opposition to the control electrodes 95 and 96 of thermionic differential detectors 98 and 100 of a phase modulation receiver. The anodes 101 and 102 of differential detectors 98 and 100 are connected in series through resistances 110 and 111, as shown. Charging potential for the anodes is supplied from a source 103 connected between the terminals of resistances 110 and 111 and the cathodes of tubes 98 and 100. The different currents resulting from the signal frequencies impressed oppositely to the control electrodes of tubes 98 and 100 flow in the resistances 110 and 111. These different currents are applied from the high potential terminals of resistances 110 and 111 to the input terminals of a radio filter circuit comprising series inductances I and I' and parallel condensers C4 connected as indicated. After passing through the filter circuits I, I', C4, the different currents flow through resistances R5, R6 to the control electrode 105 and cathode 106 of a second dynatron oscillation generator 108. Capacities C5 are connected between the terminals of the resistances R5, R6 and ground. These resistances and capacities regulate and determine the time constant of the circuit interposed between the differential resistors 110, 111 and the input electrodes of the oscillation generator 108 to regulate the sensitivity and rapidity of the control effect of the different currents on the oscillator 108.

A source 109 supplies direct current biasing potential to the grid electrode of tube 108. The differential currents from resistances 110 and 111 are superposed on this direct current potential. The output circuit 112 of the dynatron oscillation generator and modulator 108 is coupled through a link circuit 113 with a transformer 114, the secondary winding 115 of which is connected in series with the control electrodes 95 and 96 of differential detectors 98 and 100 so that the carrier frequencies developed in 112 and modulated by the differential currents in 108 are applied cophasally to the control electrodes of the differential detectors 98 and 100. This entire arrangement of the differential detectors and the frequency control means for the supplemental modulator and generator 108 is, in many respects, similar to the automatic frequency control device disclosed in United States application Ser. No. 616,803, filed June 13, 1932, now Patent #2,065,565, issued on December 29, 1936.

The detected signals appearing in the anodes of differential detectors 98 and 100 are applied by way of coupling condensers 116 and 117 to the terminals of series resistances 118, 119 and from the terminals of said resistances to the control electrodes of a pair of amplifier tubes 120 and 121 having their anodes connected through the primary winding 63' of a transformer 64'. This phase modulation receiver, including the differential detectors 98 and 100, the frequency control means 108, and the repeaters 120 and 121, impart to the modulated signals from frequency modulated dynatron 90, a distortion which is the converse of the distortion given to the initially received phase modulated signal by the frequency modulation receiver FMR. The two distortion effects add to provide in the output of transformer 64' a signal which is truly representative of the signal impressed on the original phase modulated wave. The corrected signal frequencies may be utilized from the secondary winding 65' of this transformer.

What is claimed is:

1. The method which includes subjecting a phase modulated wave to a frequency demodulation, frequency modulating a carrier wave with the demodulated wave and subjecting the frequency modulated wave to a phase demodulation.
2. In combination, means producing phase modulated waves, means subjecting the phase modulated waves to a frequency demodulation, means for frequency modulating a carrier with the demodulated waves and means for passing the frequency modulated carrier through a phase demodulating system.
3. Means for demodulating a wave modulated in phase comprising in combination a demodulation system which when energized by phase modulated waves produces an audio frequency output the amplitude of which varies substantially directly as the frequency of the signal modulations on the phase modulated wave, means for impressing said wave on said demodulator, an oscillatory circuit in which oscillatory wave energy may be caused to flow, means coupling said oscillatory circuit to said demodulator to frequency modulate the oscillatory energy flowing in said circuit, a wave demodulator which when energized by frequency modulated waves produces an audio frequency output the amplitude of which varies substantially inversely as the frequency of the modulations on the frequency modulated wave, means coupling said last named demodulator to said oscillatory circuit, and a signal utilizing means coupled to the output of said last named demodulator.
4. A correction circuit for adapting a frequency modulation receiver to the reception of phase modulated waves which includes, a tube having an oscillation circuit and a circuit for applying signals from said frequency modulation receiver to said tube to modulate in frequency the oscillations in said circuit, and a phase modulated signal demodulator of the thermionic type coupled to said tube.
5. A correction circuit for adapting a frequency modulated wave receiver to the reception of phase modulated waves which includes, a thermionic tube having an oscillation circuit and a circuit for applying signals from said frequency modulated wave receiver to said tube to modulate in frequency the oscillations in said circuit, and a phase modulated signal demodulator of the thermionic type coupled to said first tube, said demodulator being of the automatic frequency control type.
6. In signalling apparatus the combination of a demodulator normally responsive to waves modulated in frequency in accordance with signals, means for impressing waves modulated in phase in accordance with signals on said demodulator to obtain therefrom signals inherently distorted by said demodulator, a frequency modulator comprising a signal input and an oscillatory circuit, means for impressing said distorted signals from said demodulator on the signal input of said frequency modulator, and a demodulator normally responsive to waves modulated in phase in accordance with signals coupled to said oscillatory circuit whereby frequency modulated energy from said oscillator circuit of said frequency modulator is impressed on said last named demodulator to obtain therefrom resultant signals inherently distorted by said demodulator in a sense opposite to the distortion of the signal by said first demodulator to thereby obtain non-distorted signal demodulation of said wave.

7. A signalling system including, a source of wave energy the phase of which is modulated in accordance with signals, a frequency modulated wave demodulator excited by energy from said source, a wave source coupled to said demodulator and controlled as to frequency of operation thereby and wave translating means excited by controlled wave energy from said wave source.

8. The method of signalling with a source of wave energy the phase of which is modulated in accordance with modulating potentials which includes the steps of, subjecting said phase modulated wave energy from said source to a frequency demodulation, modulating the frequency of a carrier wave in accordance with the demodulated wave energy and translating the said carrier wave so modulated.

9. In a signalling system in combination, a source of wave energy modulated in phase in accordance with modulating potentials, a fre-

quency modulated wave demodulator excited by phase modulated waves from said source, a carrier wave frequency modulator excited by demodulated energy provided by said demodulator, a tunable phase modulated wave demodulator excited by modulated carrier wave from said modulator, and means excited by currents derived from said last named demodulator to control the tune thereof.

10. A correction circuit for adapting a frequency modulated wave receiver to the reception of phase modulated waves which includes, an electron discharge tube having an oscillation circuit and a circuit for applying signals from said frequency modulated wave receiver to said tube to modulate in frequency the oscillations in said circuit, and a phase modulated signal demodulator of the electron discharge tube type coupled to said first tube.
